UNITED STATES PATENT OFFICE.

VICTOR FEGLEY, OF PHILADELPHIA, PENNSYLVANIA, ASSIGNOR TO FABEC MANUFACTURING COMPANY, OF CAMDEN, NEW JERSEY, A CORPORATION OF NEW JERSEY.

INK-DISTRIBUTER FOR PRINTING-PRESSES.

1,163,073.

Specification of Letters Patent.

Patented Dec. 7, 1915.

Application filed March 19, 1914. Serial No. 825,897.

To all whom it may concern:

Be it known that I, VICTOR FEGLEY, a citizen of the United States, residing in Philadelphia, Pennsylvania, have invented certain Improvements in Ink-Distributors for Printing-Presses, of which the following is a specification.

My invention relates to certain improvements in printing presses of the type in which a rotary ink distributing disk is used and in which the inking rollers travel over the disk and over the printing form.

The invention is a companion to an application filed by me of even date herewith, Serial No. 825,908, relating to the means for supplying ink to printing presses.

The object of the present invention is to provide means for properly distributing ink as it is supplied, so that, while the ink is fed continuously to the press, it is thoroughly distributed over the disk or ink plate to insure an even impression. This object I attain in the following manner, reference being had to the accompanying drawings, in which:—

Figure 1, is a side view of an ordinary form of job printing press illustrating my invention; Fig. 2, is a view looking in the direction of the arrow, Fig. 1, of the upper portion of the press; Fig. 3, is an enlarged end view of the distributing rollers, Fig. 4, is a side view at one end of the distributing rollers; Fig. 5, is a sectional view of the first distributing roller; Fig. 6, is a perspective view of one of the small distributing rollers; Fig. 7, is a sectional view of one of the small rollers; Fig. 8, is a plan view illustrating a modification of the invention; Fig. 9, is an end view of the modification illustrated in Fig. 8; Figs. 10 and 11, are plan views illustrating other modifications of the invention. Fig. 12, is a sectional view of the ink tube; and Fig. 13, is a view illustrating the supporting rods for the rollers mounted directly in the bearings of the distributing rollers.

Referring to the drawings, 1 is the frame of the press.

2 is the bed.

50 3 is the platen.

4 is the ink distributing disk arranged at an angle, as shown.

5 is a pivoted frame carrying the inking rollers which travel over the ink distributing disk and over the type form secured to

the bed. This is the ordinary form of job press.

6 is a tube containing ink. This tube has a beveled end 7 and an opening 8, as illustrated in Fig. 12. At the opposite end of the tube is a plunger 9 which is forced forward in the tube by the ratchet mechanism 10, clearly illustrated in Fig. 1. This ratchet mechanism has an operating lever 11 which is moved each time the roller carrying frame 5 makes a movement, so as to feed a given portion of ink from the tube and into the path of the rollers. The tube, in the present instance, is located at one side of the distributing disk 4 below the center, as illustrated in Fig. 2, so that one end of each of the distributing rollers 12 and 13 take up the ink from the end of the tube and distribute it onto the edge of the disk 4.

All ink distributing disks of presses of this type have a rotary motion and in certain presses, as illustrated in the drawings, the disk is made in two sections, an inner and an outer section, and one section is rotated in one direction and the other section 80 is rotated in the opposite direction, so that, as the inking rollers travel over the disk, the ink is distributed thereon. If the ink was distributed only on the main distributing rollers 12 and 13, it would take considerable time before it would be evenly distributed over the entire disk and, in order to quickly accomplish this, I provide short rollers 14 and 15 which are of a sufficient length to extend considerably on each side of the line of ink taken from the end of the tube 6. These rollers bear against the distributing rollers 12 and 13, as shown. In the present instance, there is a single distributing roller engaged by the arm 16 mounted in the frame 5, and there are two rollers mounted in a bearing 17 engaged by an arm 18, also mounted in the frame 5. The small rollers 14 bear against the distributing roller 12 and the small rollers 15 bear against the distributing rollers 13, as clearly shown in Fig. 3.

I will first describe in detail the rollers 12 and 13 and their supports. The arm 16 has a hooked extension in which the spindle 19 105 or the roller 12 is mounted and a strap 20 is secured to this hooked extension, and mounted between a clamp plate 21 and this strap are the portions 22 of the rods 23 on which the rollers 14 are loosely mounted. The 110

clamp plate is secured to the strap 20 by screws 24 and the strap is held to the hook portion of the rod 16 by the thumb screw 25 which has a jam nut 26. Thus the rods 23 can be located in any position with respect to the rollers 12 and can be firmly held in position.

It will be understood, upon referring to Fig. 5, that the small rollers 14 have a bore considerably larger in diameter than the rods 23, so that they will freely rotate against the rollers 12 and will accommodate themselves to the yielding surface of the said rollers. The small rollers 14 are preferably made as shown in Fig. 7 and have a metallic tubular core 27 covered with a yielding casing 28 of gum or other suitable compound, but, in some instances, the rollers may be made solid without departing from the essential features of the invention.

It will be understood, upon referring to Figs. 4 and 6, that the rolls 14, as well as the rolls 15 are free to move longitudinally on their supporting rods, and in Fig. 6, I have shown collars 29 secured to the rod at such a distance apart as to enable the roller 14 to have a certain amount of longitudinal movement on the rod, as well as to turn freely thereon. This enables the roller 14 to come in contact with the distributing roller 12 and also allows it to move longitudinally thereon to more thoroughly distribute the ink taken up by the said roller.

The rolls 15 are made similar to the rolls 14 and are mounted on rods 30 shaped as shown in Figs. 3 and 4. The ends 31 of the rods are clamped upon the hooked strap 32, which is secured to the bearing 17 and to the clamp plate 33 by screws 34, and the clamp plate is rigidly secured to the bearing 17 by thumb screws 35.

36 is a U-shaped plate, which extends over the clamp plate 33 and down on each side of the bearing 17, so as to hold the parts laterally onto the bearing. The bearing has a projecting pin 37 with which the hook portion of the arm 18 engages, so as to traverse the bearings and its rollers 13 over the ink distributing disk and the form. On each of the rods 30 are collars 38 and these collars are spaced a greater distance apart than the length of the rolls 15, so as to allow the rolls to have a certain amount of longitudinal movement, the same as the rolls 14.

It will be seen by this construction that as the distributing rollers travel over the ink distributing disk and over the end of the ink tube 6, a given amount of ink is carried from the ink tube and is distributed over the disk, while the same rolls, which come in contact with the ink distributing rollers, are in line with the tube and distribute the ink taken up by these rollers over

a certain area and, as they are free to move longitudinally as well as to rotate, they quickly distribute the ink so that by the time the disk has made one revolution the ink is thoroughly distributed over said disk. 70

The construction illustrated in Figs. 3 and 4 can be applied to any printing press of the type illustrated, as the strap 32 can be hooked onto the bearing 17 and the clamp plate 32^a can be attached by a clamp screw 39 and the strap 20 can be slipped onto the head of the arm 16 and clamped thereto. 75

In Fig. 13, I have illustrated the bearing 17^a having openings for the portions 31^a of the rods 30^a carrying the rolls 15^a, and these rods are held in the position to which they are adjusted by nuts, as illustrated, dispensing with the strap and the clamp plate. 80

In Figs. 8 and 9, I have illustrated a modification of the distributing mechanism, 85 in which the rolls 14^b and 15^b are mounted on arms pivoted at 40 to a clamp 32^b. Each pair of rolls bears upon a distributing roller by a spring 41, but if it is desired to throw the rolls out of action they are simply 90 turned up on their pivots, as illustrated by dotted lines, Fig. 9; the springs holding them out of action.

It is the usual practice to have a single tube and a series of supplemental rolls at 95 one end of the distributing rollers in line with the tube, but in some instances, the supplemental rolls may be duplicated at the opposite end of the distributing rollers, which quickens the distribution of the ink, 100 and, in some instances, a tube may be located at each side of the press and the supplemental rolls may be located in line with each tube, as shown in Fig. 10.

In Fig. 11, I have shown the supplemental 105 rolls 14^c extending the full length of the rollers 12^c, and these rolls have a longitudinal motion, as well as a rolling motion against the rollers 12^c, increasing the effectiveness of the distribution, although, in ordinary practice, the long rolls are unnecessary for the proper distribution of the ink. 110

It will be seen, in all of the modifications, that the essential feature of the invention is the thorough mixing or the thorough distribution of the ink on the ink disk, so that, when the type form is supplied with ink, the ink will be evenly distributed over the type form. 115

It will be noticed, upon referring to Figs. 120 4 and 5, that the rods 23 and 30 are arranged at an angle with respect to the axis of the rollers 12 and 13. This insures the longitudinal movement of the rolls upon their rods so as to distribute the ink over a 125 portion of the surface of the rollers.

I claim:—

1. The combination in a printing press, of an ink disk; a distributing roller arranged to travel over the disk; bearings for the 130

roller; a rod carried by one of the bearings and overhanging the distributing roller; and a supplemental roll mounted on the rod and bearing upon the distributing roller.

5 2. The combination in a printing press, of an ink disk; a distributing roller arranged to travel thereon; bearings for the said roller; short overhanging rods projecting from one of said bearings; and supplemental rolls loosely mounted on the rods and having a limited longitudinal movement thereon.

10 3. The combination in a printing press, of an ink disk; distributing rollers arranged to travel over the disk; means for supplying ink to the distributing rollers located at one side of the disk; bearings for the distributing rollers; rods projecting from one of said bearings; and a supplemental roll carried by each rod, said rolls and rods being less in length than the distributing rollers, said supplemental rolls also being in line with the means for supplying ink to the distributing rollers.

15 4. The combination in a printing press, of an ink disk; a distributing roller and a pair of supplemental rolls less in length than the roller and bearing on each side of the distributing roller at one end thereof, the said supplemental rolls having a limited longitudinal movement; and means for supplying ink to the distributing roller in line with the supplemental rolls.

20 5. The combination in a printing press, of an ink disk; bearings; means for moving the bearings; distributing rollers mounted in the bearings; straps detachably secured to the bearings; and supplemental rolls carried by the straps and bearing upon the distributing rollers.

25 6. The combination in a printing press, of an ink disk; bearings; distributing rollers mounted in the bearings; means for moving the bearings so that the distributing rollers

will travel over the ink disk; a strap detachably secured to one of the bearings; clamps and clamp plates mounted on the strap; rods held in position by the clamp plate; and supplemental rolls mounted on the rods and arranged to bear against the distributing rollers.

30 7. The combination in a printing press, of an ink disk; bearings at each side of the disk; distributing rollers mounted in the bearings; a strap mounted on one side of said bearings; means for attaching the strap to the bearings; a clamp plate adjustably secured to the strap; rods having extensions mounted between the clamp plate and the strap; rolls mounted on the rods; and means for limiting the longitudinal movement of the rods.

35 8. The combination in a printing press, of an ink disk; distributing rollers arranged to travel over the disk; supplemental rolls arranged to bear upon the distributing rollers; rods on which the said rolls are mounted, the bore of the rolls being of greater diameter than the rods so that the rolls will accommodate themselves to the distributing rollers.

40 9. The combination in a printing press, of an ink disk; distributing rollers arranged to travel over the disk; short supplemental rolls arranged to bear upon one end of the distributing rollers; rods on which the rolls are mounted; said rods being arranged at an incline with respect to the axis of the rollers; and means for allowing and limiting the longitudinal movement of the rolls on their rods.

In testimony whereof, I have signed my name to this specification, in the presence of two subscribing witnesses.

VICTOR FEGLEY.
